United States Patent Office

Des. 203,487
Patented Jan. 11, 1966

203,487

DISPLAY STAND

Charles C. Van Pelt, Lake Grove, Oreg., assignor to Sawyer's Inc., Progress, Oreg., a corporation of Oregon

Filed Dec. 3, 1964, Ser. No. 82,892

Term of patent 14 years

(Cl. D80—9)

FIG. 2

FIG. 1

FIG. 3

FIG. 4

FIG. 5

FIG. 1 is a perspective view of a display stand embodying my new design;

FIG. 2 is a top plan view thereof;

FIG. 3 is an elevation view thereof;

FIG. 4 is another elevation view thereof taken at an angle of 60° to FIG. 3; and

FIG. 5 is a bottom plan view thereof.

I claim:

The ornamental design for a display stand, as shown.
